UNITED STATES PATENT OFFICE

EUGENE J. RAY, OF BEVERLY, MASSACHUSETTS, ASSIGNOR TO UNITED SHOE MANUFACTURING CORPORATION, OF PATERSON, NEW JERSEY, A CORPORATION OF NEW JERSEY

SHOE AND METHOD OF MAKING THE SAME

Application filed May 2, 1927. Serial No. 188,219.

This invention relates to the manufacture of shoes. It is herein exemplified as applied to the manufacture of standardized shoes in which various parts or units, while they are being assembled and secured together, are jigged, or relatively positioned, by the use of positioning surfaces which preferably are provided by jig holes or jig pins in or on the parts and having predetermined relations to the contours or other characteristics of the parts.

The present invention is particularly intended for use in the manufacture of standardized shoes of the type shown and described in a co-pending application filed by George E. Warren upon which was granted March 26, 1929, Letters Patent No. 1,706,504, but the invention is not limited to use in connection with shoes of that type.

More specifically, the invention relates to a novel heel pad, to a shoe having such a pad incorporated therein, and to a method of locating it accurately and retaining it effectively in its proper position in the shoe.

In most shoes the heels are attached by nails or other fastenings that penetrate to and usually are clinched upon the inner face of the insole and, therefore, it is usual to attach to the upper face of the heel portion of the insole by an adhesive a relatively thick pad of sheet felt, leather, imitation leather or the like to protect the foot of the wearer. According to the present invention, a pad, which is provided for the shoe, fulfills the well known protective function just mentioned in a superior manner and it also serves additional useful functions. For example, the illustrated pad is made of such material and of such shape as to fit, and provide a support for, the heel of the wearer and also, at its under face and curved edge, to fit the adjacent interior surface of the heel portion of the shoe. Preferably it terminates in a feather edge at its forward end and has a gradually increasing thickness longitudinally up to a maximum in the vicinity of the juncture of the body of the pad and an upstanding marginal flange.

A further and important feature of the illustrated heel pad is that it is provided

with one or more projections formed and located to engage corresponding recesses in the heel end of the shoe. Preferably, these projections are provided by two substantially conical jig pins integral with the body of the pad, projecting from its under face and so located as to engage and fit tightly at their bases corresponding cylindrical jig holes in the heel portion of the insole. Such a pad may conveniently be made of rubber and shaped in molds to approximately the desired outline and of varying thickness. The frictional grip of the jig pins upon the walls of the jig holes can be relied upon normally to retain the pad in place without requiring the use of any adhesive. Moreover, the jig pins also have the function of plugging or tightly closing the jig holes and tend to keep out from the interior of the shoe any moisture which may work its way into the jig holes which are provided in the heels according to the method set forth in the Warren application above referred to.

The invention in its preferred embodiment and as it will preferably be practiced in the manufacture of shoes will now be described in detail with the aid of the accompanying drawings and will then be defined in the appended claims.

In the drawings,

Fig. 1 is a view in perspective of the novel heel pad viewed at its upper face,

Fig. 2 is a similar view viewed at its lower face,

Fig. 3 is a transverse section through the rear jig pin, and

Fig. 4 is a central longitudinal section of the rear portion of a shoe in which the heel pad has been incorporated according to the method which constitutes the invention in one aspect.

The shoe illustrated is of a general type fully disclosed in the Warren application above referred to and includes an upper indicated generally by the numeral 10 and comprising a lining 12, an upper 14, a backstay 15 and a counter 16. 18 indicates an insole, 20 a short outsole, and 22 a heel made up, as illustrated, of a heel base 24

comprising several lifts and a rubber top section 26. In the shoe illustrated, as in the said Warren application, the heel is recessed or rabbeted as indicated at 28 to receive the rear end 20 of the outsole unit which includes in addition to the outsole 20 itself, a forepart and shank filler 30 and a metallic shank stiffener 32. A heel filler piece is indicated at 34. The upper materials, including the counter, are securely fastened to the insole 18 by a series of tacks indicated at 40, which as shown have their points clinched at the inner face of the insole. The heel base 24 is secured to the remainder of the shoe by a series of attaching nails 42 which also, as shown, are clinched at the inner face of the insole. The rubber top section 26 is likewise secured to the heel base and to the shoe by attaching nails 44 which may or may not be clinched on the insole. As fully explained in the said Warren application, the heel 22 is provided with a pair of jig holes 46 terminating short of the tread face of the heel and the insole is provided with a corresponding and alining pair of jig holes 48, these holes extending also through other elements of the shoe as illustrated and performing important jigging functions in the assembly of such elements and in other steps in the manufacture of the shoe.

The novel heel pad provided by this invention is designated generally by the number 50. It may be of any suitable material, preferably one which can be readily molded such as fairly hard and tough rubber. As illustrated in the drawings the body of the pad terminates in a marginal tapering flange 52 at the sides and rear and in a feather edge at its front end 54 so that its thickness gradually increases longitudinally to a maximum at a point indicated at 56 in the vicinity of the juncture of the body of the pad with said flange although, as clearly shown in Figs. 3 and 4, the flange merges at its upper face into the body of the pad. Moreover, the thickness of the pad transversely gradually increases from the longitudinal axis thereof outwardly. Thus the upper face of the pad forms a continuous, smooth, upper surface for engagement by the foot or heel of the wearer. Externally the flange 52 forms an oblique angle with the bottom face of the pad, the two surfaces meeting in a line 58, so that the exterior of the pad closely fits the corresponding interior surface of the shoe. Projecting from the under face of the pad are two integral, substantially conical projections or jig pins 60 which are located in a predetermined relation to the edges 54, 58 of the pad and are constructed and arranged to enter and tightly fit at their bases the jig holes 48 in the insole 18.

Thus, in the manufacture of the shoe after the heel has been attached in the manner

above described and as illustrated in Fig. 4, the heel pad, as shown in Figs. 1 to 3, is assembled with the shoe by inserting the pins 60 into the holes 48 of the insole. The relative diameters of the pins and of the holes are such that the pins at their bases tightly fit the cylindrical holes in the insole. Thus the pad not only is located with absolute accuracy in its proper position in the shoe but it is normally retained in that position by the friction of the pins with the walls of the holes and, to some extent, by the natural adhesion of the insole and lining with the closely fitting pad.

What I claim is:

1. A method of making shoes which comprises providing a shoe, having an upper, an insole, an outsole and a heel, with two jig holes in the heel portion of the shoe extending through the insole but terminating short of the tread face of the heel and assembling with said shoe a molded heel pad having two integral, substantially conical jig pins projecting from its under face and extending into and tightly fitting said jig holes.

2. A method of making shoes which comprises providing a shoe having an upper, an outsole, a heel, and an insole with two jig holes in its heel portion, molding a heel pad exteriorly approximately to fit the adjacent portion of the shoe and interiorly approximately to fit the foot of the wearer and with two integral projections extending from its under face, and then assembling said pad in said shoe with the projections extending into and tightly fitting the top edges of said jig holes.

3. In a shoe, an upper, a sole and a heel in combination with a rubber heel pad, molded exteriorly approximately to fit the adjacent portion of the shoe and interiorly approximately to fit the foot of the wearer and having two integral, substantially conical projections extending from its under face and tightly fitting recesses in the heel portion of the shoe.

4. In a shoe, an upper, an insole and a heel in combination with a heel pad having a plurality of jig pins integral therewith and extending from its under face and fitting at their bases a corresponding number of jig holes in the heel portion of the insole.

5. In a shoe, an upper, a sole and a heel in combination with another bottom part having one or more integral conical projections extending therefrom and at their bases fitting recesses in an adjacent portion of the shoe.

6. In a shoe, the combination of an upper, an insole provided with cylindrical jig holes in its heel portion and a heel, with a heel pad having two integral, substantially conical jig pins projecting from its under face,

the bases of said pins being constructed and arranged to engage and fit tightly the top edges of said cylindrical jig holes.

7. A molded heel pad for a shoe having two integral, substantially conical jig pins projecting from its under face and located to engage and fit tightly at their bases corresponding cylindrical jig holes in the heel portion of the insole of the shoe.

8. A molded rubber heel pad for a shoe shaped exteriorly to fit the adjacent portion of the shoe and having an integral, tapering projection extending from its under face and located to engage and fit along a line adjacent to its base a hole in the heel portion of the insole of the shoe.

9. A relatively hard, molded, rubber, heel pad for a shoe having a marginal, tapering flange forming an oblique exterior angle with the bottom face of the pad so as to fit the adjacent portion of the shoe and also forming a continuous smooth surface with the upper face of the pad, the longitudinal thickness of the pad gradually increasing from a feather edge at its front end to a maximum thickness adjacent to said flange.

10. A relatively hard, molded, one-piece, heel pad for a shoe having a marginal, tapering flange forming an oblique exterior angle with the bottom face of the pad so as to fit the adjacent portion of the shoe and also forming a continuous smooth surface with the upper face of the pad, the thickness of the pad longitudinally thereof gradually increasing from a feather edge at its front end to a maximum thickness adjacent to said flange and its thickness transversely gradually increasing outwardly in both directions from the longitudinal axis of the pad so that said upper face approximately fits the heel of the wearer.

11. A relatively hard, molded, heel pad for a shoe having a marginal flange and a continuous, smooth, upper surface shaped approximately to fit the foot of the wearer and shaped at its under face and curved edge to fit the adjacent interior surface of the heel portion of the shoe and having one or more integral projections extending from said under face, the longitudinal thickness of the body of the pad gradually increasing from a minimum at its front edge to a maximum adjacent to said flange.

In testimony whereof I have signed my name to this specification.

EUGENE J. RAY.
